Craig S. Losie

UNITED STATES PATENT OFFICE.

CRAIG S. LOSIE, OF HORNELLSVILLE, NEW YORK.

ADJUSTABLE FLOORING-JACK.

SPECIFICATION forming part of Letters Patent No. 686,622, dated November 12, 1901.

Application filed February 24, 1899. Serial No. 706,752. (No model.)

To all whom it may concern:

Be it known that I, CRAIG S. LOSIE, of the city of Hornellsville, in the county of Steuben, and in the State of New York, have invented certain new and useful Improvements in Flooring-Jacks; and I do hereby declare that the following is a full, clear, and exact description thereof, reference being had to the accompanying drawings, and to the letters of reference marked thereon, making a part of this specification.

The object of my invention is to provide an improved means for drawing or wedging up any tongue-and-grooved material of various thicknesses in whatever way, shape, or manner the same may be applied to buildings.

My improvement consists, essentially, in a lever that has an adjustable pin attached to it, which acts as a fulcrum to the lever, which turns in a slot cut in a head, which is enlarged at its top to form a place to strike and drive pin in. The head is an extension of a sleeve that travels on the lever, and it is moved to and held in any desired position by a thumb-screw placed in a notch and upon a pin that is secured in an upset on the lever and an arm with two sets of jaws attached to it, (one set at each end.) Upper jaws are adjustable and are raised and secured with a thumb-screw, so as to coincide with thickness of tongue of the board to which the jack is applied. The lower jaws are an extension of and part of arm and are toothed. These teeth enter the wood under the tongue of board and prevent the same from slipping out. Jaws have rubber cushions that conform to their shape and are secured to the upper jaws.

In the accompanying drawings, Figure 1 is a plan view of adjustable flooring-jack containing my invention. Fig. 2 is a plan view of arm. Fig. 3 is a vertical horizontal section of Fig. 1 in line xx . Fig. 4 is a side view of pin.

A is the metal lever.

A' is a notch cut in A.

u is an upset to strengthen A and to receive p , upon which the thumb-screw S turns.

B is a metal arm, so constructed as to allow the lever to describe an arc of a circle and is secured to A with rivets b and screw b' , Fig. 3.

C represents metal jaws, of which there are two sets, one set at each end of B.

C' is a partial view of lower jaw, which is an extension of B and is toothed at c' , Figs. 2 and 3.

c is a rubber cushion and conforms to shape of jaws and is secured to upper jaws with 60 screws s , Fig. 2. These upper jaws travel on guides. Back guide is square in form and is part of lug c'' , Fig. 2.

c'' is front guide and is secured to upper jaw and passes through hole in lug c'' , Fig. 65. 2, when jaws are raised, which is done with thumb-screws S , Figs. 1, 2, and 3.

D is metallic sleeve that travels on A and fits in notch A' and is moved to and held in any desired position by thumb-screw S , Fig. 70 3, which passes through its center, and it has head H formed upon it, which has face d' raised upon it and slot j cut out to receive pin E, Fig. 3.

E is a metal pin which acts as a fulcrum to 75 the lever and turns in slot j of head H, Fig. 3, and has bearing at its upper end and shoulders e' at E, Fig. 4, and also has a bearing on the circumference of head H at e'' , Fig. 3, thereby relieving pin e , Fig. 3, of all unnecessary strain.

It will be seen that by placing the jack in a perpendicular position and raising the jaws C with thumb-screw S to coincide with the tongue of board and driving on face d' , which 85 forces in pin E, Fig. 3, to secure a purchase, and then pushing on the lever it will draw board up tight and hold it there until it is secured, when the jack can be released; also, that the rubber cushions c , Fig. 3, will prevent all marring and jamming of the boards. 90

This invention can be used on boards that are not matched, as the teeth c' , Fig. 2, will penetrate the board far enough to hold it while it is being drawn up.

95

What I claim as my invention is—

An adjustable flooring-jack comprising a lever, a screw in said lever, a head mounted on and adjustable by said screw, a pin carried by said head, jaws adjustable to the size 100 of the boards to be operated upon, one set of jaws having rubber cushions and one set being serrated, substantially as set forth.

In testimony that I claim the foregoing I have hereunto set my hand this 17th day of 105 February, 1899.

CRAIG S. LOSIE.
